EARTH MOVING SCRAPER

James S. Stewart, Sidney, Ohio, assignor to The
Slusser-McLean Scraper Company, Sidney,
Ohio, a corporation of Ohio

Application November 29, 1933, Serial No. 700,282

5 Claims. (Cl. 37—140)

This invention relates to new and useful improvements in earth moving scrapers.

It is one of the principal objects of my invention to provide an earth moving scraper having 5 load control means which enables it to be placed in a loading position at any time without stopping the tractor. In other types of scrapers, it is not possible to pull the bowl back into a loading position, after it is unloaded, without stopping 10 the tractor.

It is another object of my invention to provide a scraper which can be easily operated by handles to pick up a load and unload it at any desired time. The operating parts of the scraper 15 are in almost perfect balance, and are under the operator's control at all times.

Another object of my invention is the provision 20 of a spreading stop that may be adjusted to regulate the depth at which the unloaded dirt may be spread by the scraper.

Other important and incidental objects will be brought out in the following specification and particularly set forth in the subjoined claims.

In the accompanying drawings illustrating my 25 invention, Figure 1 is a perspective view of my scraper, showing the general arrangement of its various elements. Figure 2 is an end view of the same, and Figure 3 is a partial top plan view thereof, showing the bowl mounting bearing in 30 section.

Referring now to the drawings, the numeral 1 indicates a triangular hitch or towing frame for an earth moving scraper, consisting of a central 35 towing member 2 and converging side members 3 and 4. At their forward ends where they meet, these members are secured together by bolts 5, 5. At the extreme forward ends of the members 3 and 4, I have provided a series of vertically aligned 40 holes 6 to provide an adjustable connection with the towing bar of a tractor or other prime mover not shown. (See Figure 1.)

At the rear end of the towing frame a cross bar 7 is secured between the rear ends of the side members 3 and 4, and at its center, it is bolted 45 or otherwise attached to the rear offset end 8 of the center member 2 to form a rigid towing frame.

Projecting rearwardly from the hitch frame, and secured by bolts 9, to the outer face of the side members 3 and 4 are parallel end plates 10 50 and 11. At its rear end, each of these end plates is formed with a horizontal, elongated, bearing receiving aperture 12, reinforced by a peripheral flange or pad 13, welded or otherwise secured to the outer face of the end plate. (See Figures 1, 55 2 and 3.)

In front of the apertures 12, and depending from each of the end plates 10 and 11, is a torque arm 14, having therein a rearwardly inclined elongated slot 15, surrounded by a reinforcing pad 16 similar to the pads 13, 13. The function of the aperture 12 and slot 15 will be hereinafter described.

Adjacent the inner face of each one of the end plates 10 and 11, and projecting rearwardly in alignment therewith, are freely mounted latch 10 plates 17 and 18, each having a profile similar to the plates 10 and 11, except however that at their forward free ends these latch plates terminate in forwardly inclined arms 19. Intermediate these arms 19 and the rearward end of the latch 15 plates 17 and 18, the latter are formed with raised central flanges 20.

Each of the latch plates 17 and 18 is provided with a torque arm 21, similar to the torque arms 14. Welded or otherwise secured to the outer 20 face of each arm 21 is a torque stud 22, adapted to be slidably received by the elongated slot 15 in its adjacent end plate 10 or 11.

The rearward ends of these latch plates are 25 apertured to receive therein the reduced inner ends of a flanged trunnion bearing 23. Each of these bearings 23, 23 is formed with an axial bore 24 in which there is rotatably mounted the outer reduced end 25 of a flanged trunnion 26. Intermediate the outer end 25 and a bolt flange 27 30 formed at its inner end, each trunnion has a center peripheral flange 28. When the trunnion bearings 23 are inserted in the latch plates 17 and 18, and against their outer faces, the outer reduced end 25 of the trunnions will be received by 35 the bores 24 from the opposite or inner faces of the latch plates to bring the flanges 28 against said faces and trunnion bearings 23.

As shown in Figures 2 and 3, I have provided 40 for each trunnion an inverted U shaped thrust collar 29 having in one face thereof a recess 30 in which the flange 28 is received. This collar 29 is secured to the latch plate by bolts 31, 31 passing through its flange, the latch plate and the flange of the trunnion bearing 23, to thus 45 firmly attach each trunnion bearing to its respective latch plate and secure the trunnion against endwise movement. (See Figures 2 and 3.)

The inner flanged end 27 of each trunnion is 50 attached by bolts 32 to the center of a circular disc-like head 33 at each end of a scraper bowl 34 positioned between the latch plates 17 and 18 and in alignment with, and behind, the towing or hitch frame 1. (See Figures 1, 2 and 3.)

55

Each of the heads 33, 33 is reinforced by a peripheral L shaped flange 35, whose radial leg is secured to the head by rivets 36. Formed on the lower side of each head is a flat surface in the plane of the earth and against which there is secured by rivets 37, through the flange 35 on each head, a scraper bit or blade 38.

The scraper blade 38 extends transversely between the heads 33, 33 to form a flat horizontal bottom for the scraper bowl 34. Along its forward edge the blade 38 is beveled to provide an earth biting edge 39, and at its rearward edge, the blade is attached to a bottom transverse flange 40 formed on the lower edge of the curved rear wall 41 of the bowl, practically quarter circular in extent, and welded or otherwise secured to the periphery of the heads 33, 33 and their reinforcing flanges 35, 35.

Also secured to the flanges 35, 35 on the heads 33, 33, and in front of the trunnions 26, 26 are arcuate wear shoes 42, 42 whose lower ends terminate sufficiently above the forward edge of the blade 38 so that they will not impede the movement of earth into the bowl. (See Figures 1, 2 and 3.) On each head 33, 33 I have provided a series of circumferentially spaced holes 43 to receive bolts 44 by which there is adjustably attached to the outer face of each head, and in front of the trunnions 26, 26, a loading stop 45; and behind the trunnions an unloading stop 46. These stops 45 and 46 are similar, and consist of curved, flat bases 47 having therein apertures to receive the bolts 44. Projecting axially from the center of the base 47, and thence at a right angle and radially, is a stop lug 48. (See Figures 1, 2 and 3.)

The lug 48 on each loading stop 45 is adapted to be engaged by a roller 49, freely mounted in the forked outer end 50 of a lever arm 51, whose opposite offset end 52 is pivotally attached by a bolt 53 to the raised flange 20 on its respective latch plate. When thus engaged, the lever arm 51 will effectively resist the rotation of the scraper bowl 34 as a wheel.

Above the roller mounting, there is pivotally attached to the forked outer end 52 of the lever arm 51, a hinged link 54 provided at its center with a hinged joint 54^a. Adjacent this hinged joint a marginal flange 55 is formed on the lower end 56 of the link to engage the side of the link member 57 adjacent the joint 54^a, to permit the hinged joint to break upwardly only, when the lower end 56, secured to a transverse release shaft 58, is rotated.

The hinged link 53, when in its extended position as shown at Figure 1, will prevent movement of the lever arm 51. Also, when the shaft 58 is rotated, the hinged joint will be broken and the lever arm 51 and the roller 49 will be withdrawn from the path of the loading stop 45.

Beyond the arms 19, there is attached to each end of the shaft 58, a short lever arm 59, and between its outer end and the bolt 53, there is a helical tension spring 60 to return and hold the lever arm in its normal position. The shaft 58 has attached thereto, near its center, a lever arm 61. In its upper end there is an aperture 62 through which a rope or cable 63 may be secured to enable the operator seated on the tractor to draw it forwardly, its rearward travel being accomplished by the spring 60.

When this lever arm 61 is drawn forwardly, the rollers 49 will be withdrawn from the path of the loading stops 45, 45, and as the loaded scraper bowl is drawn forwardly, it will rotate

as a wheel until the unloading or spreading stops 46, 46 engage the rollers 49, 49, which have returned to their normal positions as shown in Figures 1 and 2.

With the unloading stops in engagement with the rollers 49, 49, the wear shoes will be beneath the bowl to support its weight upon the earth; and when the rotation of the bowl is arrested by the unloading stop 46, the forward beveled edge 39 of the blade 38 will be positioned a desired distance above the earth to level off the material discharged from the bowl and to a desired and adjustable depth.

By adjusting the loading and unloading stops 45 and 46 through utilization of the various bolt holes 43, varying degrees of "bite" may be secured, as well as varying depths to which the discharged material will be spread.

When in operation and while being drawn forwardly, the bowl has a tendency to turn counterclockwise by virtue of the tractive pull exerted on the torque studs 22 acting as crank pins. Also the trunnion bearings will move rearwardly extensively with the apertures 12, 12, whereupon the torque studs 22 will rise or ride against the upper end of the slots 15, 15, thus slightly elevating the forward edge of the blade 38. This also causes the arms 19, 19 to rise.

In order to counteract this tendency and force the blade downwardly into the earth, I have provided the following means. Pivotally attached to the end of each arm 19, is a short curved link 64, whose other end is pivotally secured to a stud 65 attached to the outer end of a lever arm 66. This arm is adapted to be rotated by a transverse control shaft 67, journaled in side bearings 67^a, secured to the forward end of the end plates 10 and 11 adjacent the cross bar 7 and a center bearing 68 also secured to the cross bar 7 near the center member 2. When the shaft 67 is rotated clockwise as viewed in Figure 2, the arms 19, 19 will be drawn downwardly, to counteract the tendency of the torque studs to turn counterclockwise, and since the torque connection through the torque studs 22 is below the center of gravity, and relatively close to the scraper blade, a uniform cut may be obtained, regulated by the downward pull on the arms 19, 19.

Secured to the shaft 67 near its center bearing, is a forwardly projecting lever arm 69. This lever arm is connected at its outer end by a plate member 70 to a forwardly inclined lever arm 71 through whose upper apertured end a control cable 72 is passed for actuation by the operator. The greater the shaft 67 is rotated by the lever arm 69, the more the arms 19, 19 will be depressed, with a consequent increase in the cut or "bite" of the scraper blade. However, the extreme downward movement of the arms 19, 19 will be limited by their engagement with the rear inclined faces 73 of the side members 3 and 4 of the hitch or towing frame.

Having described my invention, I claim:

1. In a device of the type described, a bowl, a bit secured to said bowl, an inner frame in which said bowl is pivotally mounted, a towing frame outlying the inner frame, and formed with oppositely disposed axial slots and below the latter, with upwardly inclined slots, bearings for the bowl projecting from the inner frame into the axial slots in the towing frame, studs projecting from the inner frame into the upwardly inclined slots in the towing frame, stop means to prevent the bowl from turning as a wheel when it is drawn forward by the towing frame, and lever

means for preventing an upward movement of the inner frame when the bowl is drawn forward in a loading position.

2. In a device of the type described, a scraper bowl, an inner frame in which said bowl is pivotally mounted, a towing frame, outlying the inner frame, and formed with oppositely disposed axial slots and below the latter, with upwardly inclined slots, bearing means for the bowl projecting from the inner frame into the axial slots in the towing frame, projections on the inner frame extending into the upwardly inclined slots in the towing frame, stop means to prevent the bowl from turning as a wheel when it is drawn forward by the towing frame, and means for preventing an upward movement of the inner frame when the bowl is drawn forward in a loading position.

3. In a device of the type described, a scraper bowl, an inner frame in which said bowl is pivotally mounted, a towing frame, outlying the inner frame, and formed with oppositely disposed axial slots and below the latter, with upwardly inclined slots, bearing means for the bowl projecting from the inner frame into the axial slots in the towing frame, projections on the inner frame extending into the upwardly inclined slots in the towing frame, stop means to prevent the bowl from turning as a wheel when it is drawn forward by the towing frame, a transverse shaft, linkage connected between said shaft and the front end of the inner frame, and a lever secured to said shaft whereby, when said lever is pulled forwardly by the operator, an upward crank movement of the inner frame will be prevented.

35 4. In a device of the type described, a scraper

bowl, a blade secured to said bowl, an inner frame, oppositely disposed axial bearing cups carried by the rear side portions of the inner frame, trunnions on said bowl adapted to enter said bearing cups whereby the bowl may turn freely in them, a towing frame outlying the inner frame and formed with oppositely disposed axial slots, and below the latter with upwardly inclined slots, said bearing cups projecting from the sides of the inner frame into the axial slots in the towing frame, torque studs projecting from the inner frame into the upwardly inclined slots of the towing frame, stop means to prevent the bowl from turning as a wheel when it is drawn forwardly by the towing frame, and hand control means for preventing an upward movement of the inner frame when the bowl is drawn forwardly in its loading position.

5. In a device of the type described, a scraper bowl, an inner frame, oppositely disposed bearings carried by the rear side portions of the inner frame, trunnions on said bowl adapted to enter said bearings whereby the bowl may turn freely in them, a towing frame outlying the inner frame and formed with oppositely disposed axial slots, and below the latter with upwardly inclined slots, said bearings projecting from the sides of the inner frame, torque studs projecting from the inner frame into the upwardly inclined slots of the towing frame, stop means to prevent the bowl from turning as a wheel when it is drawn forwardly by the towing frame, and control means for preventing an upward movement of the inner frame when the bowl is drawn forwardly in its loading position.

JAMES S. STEWART. 35
